HAIR WAVING SYSTEM

Armand Caldora, Brooklyn, N. Y., assignor of
one-half to Pierre Michielli, Woodhaven,
N. Y.

Application February 10, 1939, Serial No. 255,583

13 Claims. (Cl. 132—36)

The present invention relates to a hair waving system and particularly relates to a clamp, curler, container and associate devices which are useful in connection with the curling of the human hair. 5 It is among the objects of the present invention to provide a simple, inexpensive and readily manipulated arrangement and system which may be utilized either at home or in beauty parlors for hair waving and particularly for Croquignole 10 waving.

Another object is to provide a simple, inexpensive hair waving method and system by which it will be possible to wave the hair, particularly according to the Croquignole method, without the 15 use of electricity, without the necessity of unduly confining the movements or position of the person having the hair waved, without danger of burning or overheating the hair, with assurance that the head and scalp will be fully protected 20 from injury and hot liquids and with assurance of maximum comfort to the person whose hair is being waved.

Other objects will be obvious or will be apparent during the course of the following specification.

In accomplishing the above objects, it has been found most satisfactory to provide a one piece molded or otherwise formed rubber or flexible box device having a clamp to hold the strand of hair 30 to be waved adjacent the scalp and also forming a receiver for a curler and for a hair waving pad and a cover to enclose the pad and the curler with the coil of hair thereon during the waving treatment.

Desirably, the rubber box has formed therein a resilient member which acts to press the bottom of the box together to form a seal and clamp and also to lock the two ends of the box together when the clamp is in operative position.

The curler itself may be formed of two elongated elements of wood, or of a molded resin or plastic or less desirably of a light weight metal, which may be resiliently and pivotally connected together at one end with a rubber or resilient 45 band and which may be provided with peripheral teeth to engage a pawl device fixed in the wall of the rubber device.

The above and other objects will appear more clearly from the following detailed description when taken in connection with the accompanying drawings, and will illustrate a preferred embodiment of the inventive idea.

Figure 1 shows a perspective view of a woman's head illustrating the manner of attachment and

the utilization of the hair waving arrangement of the present application.

Figure 2 is a top perspective view showing the box with the curler having a strand of hair wound thereon and with the hair waving pad in position. 5

Figures 3 to 6 show the hair curler before attachment to the hair and before placement in the box of Figure 2; Figure 3 being a side view in elevation; Figure 4 being a longitudinal sectional view and Figures 5 and 6 being transverse 10 sectional views on the lines 5—5 and 6—6 of Figure 3.

Figure 7 is a perspective view of the hair waving pad which may be folded and placed in the box in the manner indicated in Figure 2. 15

Figures 8 to 12 illustrate the box construction, Figure 8 being a top perspective view of the box in open position; Figures 9, 10 and 11 being transverse sectional perspective views on the lines 9—9, 10—10 and 11—11 of Figure 8 and Figure 12 20 being a bottom view.

Figures 13 to 19 illustrate another box construction, Figure 13 being a top perspective view with the lid open and the box separated with a part of the front wall broken away; Figure 14 25 being a similar perspective view; Figures 15 and 16 being transverse sectional views on the lines 15—15 and 16—16 of Figure 14; Figure 17 being an end view of the clamping arrangement and Figures 18 and 19 being respectively sectional 30 views upon the lines 18—18 of Figure 17, Figure 18 showing the clamp in position on Figure 17 and Figure 19 showing a clamp in open position.

Referring to Figures 1 to 10, a box A which may be formed of rubber or some other suitable 35 synthetic plastic material is provided with a receptacle B, a cover C and a clamp base portion D.

The box is designed to receive the curler E which carries the strand of hair F in wound or coiled position, the box A may also receive the 40 hair waving pad G in folded condition, as shown in Figure 2.

The latch construction H is carried by the body of the box A.

Referring specifically to the box construction 45 which is best shown in Figures 8 to 11, the box may be molded of relatively flexible rubber or some other similar plastic and bendable material with a back portion 20 and a front portion 21.

The side walls 22 and 23 are molded integrally 50 with the back wall 20.

Extending from the upper edge of the back wall is the cover C having the sloping end edges 24, and the side edges 25.

Downwardly projecting fins 26 of the cover are 55

designed to fit inside of and against the inner faces 27 of the side walls 22 and 23 so as correctly to locate the cover.

The cover is also provided with a slit or slot 28 which is designed to engage the finger 29 molded integrally with the front wall 21.

As best shown in Figure 12, the walls 21-22 are provided with bottom portions 30 and 31 which are joined together at 32 (see Figure 12) and which are split at 33 for a major portion of the length of the bottom of the box A, as best shown in Figures 9, 10, and 11.

The split has the vertical flat abutting faces 34, 35 on either side of the projection 36 and recess 37.

As indicated successively from Figures 9 and 10, the bulge at 36 becomes less and less as it approaches the unsplit portion 32 of the bottom of the box A. It is also possible to continue the bulge 36 without any successive diminution of size.

The combination of the bulge 36 and the recess 37 which closely interfit with one another not only assures a tight clamping of the strand of hair, but also prevents any leakage of liquid from the interior of the box on to the scalp.

The bottom of the box, as best shown in Figure 12 is provided with feet which are arranged in three rows designated respectively 38, 39 and 40. The end feet 38b, 39b, and 40b, adjacent the clamp H have extensions 38a below the wall 22 and the end of the side 21.

Molded into the bottom portions 30 and 31 is the U-shaped spring 41 which has an end or base portion 42 and side portions 43 and 44.

The end of the portion 43 has an extension 45 extending along the end of the bottom portion 31 and terminating in the turned over portion 46. The element 45 forms a part of the latch H and the other part of the latch is formed by the turned-out tongue 47, the end of which is designed to engage and snap behind the rolled over portion 46.

The tongue 47 forms a continuation of the end of the portion 44.

The inside portion of the wall 23 is recessed, as indicated at 48 to receive the end portion of the curler E while the other wall portion 22 is recessed, as indicated at 49 to receive the other end portion.

The recess 49 is continued by the rounded recessed portion 50 of the front wall 21.

As shown best in Figure 9, embedded in the side wall 22 is the inverted V-shaped spring member 51, one leg 52 of which projects into the opening 49.

The leg 52 forms a pawl which cooperates with the curler.

It is noted that the box may be clamped together by engaging latch elements 45 and 47 and the cover may be closed by engaging the slit 28 with the tooth or tang 29.

The fins 26 will contact the inside faces 27 of the end walls and will correctly position the cover when closed, with the cover resting closely on the upper portions of the walls 22 and 23 and 21 so that there is a tight closure on all sides in combination with the interfitting of the projecting portion 36 and the ribs 37.

The curler which is received in the box of Figures 8 to 11 is best shown in Figure 3.

The curler is formed of two elongated elements 53 and 54 which are curved at 55 and 56. The curved portions are designed to receive a

coil of hair, the end of which is to be clamped between the flat abutting portions 57.

The rear end of the curler E is provided with projecting portions 58 and 59 which are bevelled off at 60 so that the two portions 58 and 59 may be grasped between the fingers to open the curler and permit the insertion of a strand of hair.

Inside of the bevelled portion 60 is the recess 61 in the lower member 54 into which fits the projection 62 in the upper member 53, the interfitting of the recess 61 and the projection 62 forming the pivot mount upon which the elements 53 and 54 may be separated.

Beyond the pivot point is the groove 63 which extends around the entire curler E which may receive a rubber band 64 or a spring or some other member designed to press the two surfaces 57 together.

Next to the rubber band or resilient member 64 is the ratchet 65 which fits into the recess 49-50 of the box A and cooperates with the pawl 52.

On the other side of the ratchet the element 53 and 54 are provided with a projection 6 which forms a limit for the strand of hair on one side, the projection 67 on the end 68 of the curler forming a limit for the strand at the other end of the curler.

To keep the elements 53 and 54 aligned, the upper element 53 is provided with a fin 69 which fits into a recess 70.

The cylindrical end portion 68 is designed to be received in the recess 48 of the box of Figure 8 to 11.

The intermediate portion of the curler between the end portion 68 and the ratchet 65 is received within the box and is designed to be enclosed by the cover 24.

The hair waving pad G, which may be folded over and inserted in the box in the manner indicated in Figure 2, has a backing 70a of foil which is folded over, as indicated at 71, upon a permeable fabric or cloth bag 72 having the paper or foil edges 73.

The bag is designed to hold a chemical which upon being moistened will generate a large amount of heat, and steam sufficient to steam the strand of hair enclosed in the box C.

In operation, a number of strands of hair 1 are selected, as indicated in Figure 1. Each strand is then inserted through the base of the box and clamped between the recess 37 and the ridge 36 by closing the latch H.

The strand of hair is then saturated with a hair waving solution and is clamped between the faces 57 of the curler E and the rest of the strand is wound up upon the curler E between the projections 66 and 67.

When the hair has almost been completely wound, the curler with the coil of hair upon it is placed in the box with the portion 68 of the portion E being placed in the recess 48 and the ratchet 65 being caused to engage the pawl 52.

Then, the hair may be tightened up upon the curler E by cooperation of the ratchet 65 and the pawl 52. Then the pad G is moistened, folded and inserted in the box preferably against the wall 20.

Then, the cover is closed by latching the slit 28 upon the projection 29.

When there has been sufficient heat treatment and steaming of the hair, the cover C may be lifted. Before unwinding the hair the same should be thoroughly cooled. The pad G is then removed, the curler E removed, the hair strand

F unwound before or after the box A is removed from the hair by unlatching the element H.

The hair after release from the curler E may be combed out, moistened or otherwise treated to complete the waving operation.

It will be noted there is no electricity needed, that the operation is relatively simple, that the flexible material of the box A assures a perfect seal around all edges and assurance is had that a thorough steaming is obtained.

The elements are relatively simple and inexpensive and may be manipulated with a minimum of inconvenience to the person having her hair waved and to the operator or beautician.

15 The use of the box A eliminates the usual clamp, scalp protector and various types of enclosures giving a less expensive apparatus and the shape and size of the box permits the pad to be used in folded condition without causing it to 20 be wrapped upon the hair.

Furthermore, the closure of the box permits the pad to be placed separately from the hair and alongside of the hair, to give a most satisfactory steaming operation which results in a 25 better treatment of the hair.

In the alternative box construction shown in Figures 13 to 19, the box may be made of a plastic material such as rubber except that the end wall 15 may be provided with an opening 16 to receive 30 the end portion 68 of the curler.

The bottom of the box A may have a series of small projections 17 instead of the relatively large elongated fins 38, 39 and 40 of Figure 12.

From the end wall portion 18 extends the plate 35 element 19 which is designed to engage the circular latch 80 having a projection 81 and a flat portion 82 which is positioned so as to slide along the projection 19 when the latch is applied in the manner indicated in Figure 19.

40 The latch has a pivotally mounted bar 83 which is pivotally connected at 85a to a projection 85 from the side wall portion 18a attached to the back wall 80.

The two side wall portions 18 and 18a are provided with recessed portions 81, 82 which receive 45 the ratchet 65.

The wall 19 is provided with the embedded plate member 83a having the serrated edge portion 84 which serves as a pawl to cooperate with 50 the ratchet 65.

It will be noted that the split bottom has two sections 87 which have flat abutting faces 86 instead of the combination 36-37 of the box structure of Figures 8 to 11.

55 It is apparent that the specific illustrations shown above have been given by way of illustration and not by way of limitation and that the structures above described are subject to wide variation and modification without departing 60 from the scope or intent of the invention, all of which variations and modifications to be included within the scope of the present invention.

What is claimed is:

1. A hair waving enclosure consisting of a box 65 formed of a flexible self-sealing rubber-like material having a split bottom to receive and clamp a strand of hair and a cover.

2. A hair waving enclosure consisting of a box 70 formed of a flexible self-sealing rubber-like material having a split bottom to receive and clamp a strand of hair, a clamp to clamp said split bottom together and recesses to receive a curler.

3. A hair waving enclosure consisting of a box 75 formed of a flexible self-sealing rubber-like material having a split bottom to receive and clamp

a strand of hair, a clamp to clamp said split bottom together and recesses to receive a curler, one of said recesses having a pawl and the portion of the curler fitting therein being formed as a ratchet.

4. A hair waving enclosure consisting of a box formed of a flexible self-sealing rubber-like material having a split bottom to receive and clamp a strand of hair, a clamp to clamp said split bottom together and recesses to receive a curler, said 10 material consisting of molded rubber.

5. A hair waving enclosure consisting of a box formed of a flexible self-sealing rubber-like material having a split bottom to receive and clamp a strand of hair, a clamp to clamp said split 15 bottom together and recesses to receive a curler, said clamp being molded into the base of said box.

6. A hair curler consisting of two elongated members, provided with a pivotal connection, a resilient band to clamp said members together 20 to grasp the outer end of a strand of hair, said members being also provided with a tapered portion upon which the strand of hair may be coiled, the abutting faces of said elements adjacent said pivotal connection being respectively provided 25 with a longitudinally directed recess and with a fin fitting therein holding said elements in alignment when separated or moved together.

7. A hair curler consisting of two elongated elements having flattened abutting faces and 30 having central concave portions upon which is to be wound a strand of hair, the ends of said elements beyond said concave portions being provided with cylindrical extensions, said cylindrical extensions being provided with outstanding 35 ridges adjacent said concave portions to hold the hair in position upon said concave portions and pivotal connection means at one end of said elements beyond said ridges.

8. A hair curler consisting of two elongated elements having flattened abutting faces and having central concave portions upon which is to be wound a strand of hair, the ends of said elements beyond said concave portions being provided with cylindrical extensions, said cylindrical 45 extensions being provided with outstanding ridges adjacent said concave portions to hold the hair in position upon said concave portions and pivotal connection means at one end of said elements beyond said ridges, said pivotal connection 50 means including a rubber band encircling said cylindrical extensions.

9. A hair curler consisting of two elongated elements having flattened abutting faces and having central concave portions upon which is to be wound a strand of hair, the ends of said elements beyond said concave portions being provided with cylindrical extensions, said cylindrical extensions being provided with outstanding ridges adjacent 55 said concave portions to hold the hair in position upon said concave portions and pivotal connection means at one end of said elements beyond said ridges, said pivotal connection means including a transverse groove in one of said elements and a transverse ridge in the other of said 60 elements.

10. A hair curler consisting of two elongated elements having flattened abutting faces and having central concave portions upon which is to be wound a strand of hair, the ends of said 65 elements beyond said concave portions being provided with cylindrical extensions, said cylindrical extensions being provided with outstanding ridges adjacent said concave portions to hold the hair 70 in position upon said concave portions and pivotal connection means at one end of said elements beyond said ridges.

75

- total connection means at one end of said elements beyond said ridges, said cylindrical extensions being elongated at said pivotal connection means and including a ratchet positioned adjacent said outstanding ridge and a rubber band positioned next to said ratchet and the abutting faces of said elongated cylindrical extensions being provided respectively with longitudinal and transverse grooves and with longitudinal and transverse ridges fitting in said grooves and the ends of said elongated cylindrical extensions being inwardly bevelled so as to permit separation of said flattened abutting faces.
11. A self-sealing rubber hair waving enclosure
- 15 to receive and hold a curling rod holding a strand of hair and an exothermic hair waving pad and serving to form a tight seal against the escape of steam or moisture from the interior thereof when applied to the head, said enclosure consisting of
- 20 a box formed of an integral piece of rubber material having a split bottom to receive and clamp a strand of hair adjacent the scalp and serve as a scalp protector having side recesses to receive a curling rod, having a pawl to enable tightening and winding up of said curling rod and to hold said curling rod in position and having a cover flap to enclose the upper end thereof and form a tight seal, the split bottom of said enclosure having a U-shaped member molded therein,
- 25 the ends of which project to form a latch.
12. A self-sealing rubber hair waving enclosure to receive and hold a curling rod holding a strand of hair and an exothermic hair waving pad and serving to form a tight seal against the
- 30 escape of steam or moisture from the interior
- 35

thereof when applied to the head, said enclosure consisting of a box formed of an integral piece of rubber material having a split bottom to receive and clamp a strand of hair adjacent the scalp and serve as a scalp protector having side recesses to receive a curling rod, having a pawl to enable tightening and winding up of said curling rod and to hold said curling rod in position and having a cover flap to enclose the upper end thereof and form a tight seal, the split bottom of said enclosure having a U-shaped member molded therein, the ends of which project to form a latch, said pawl being molded into the body of said enclosure.

13. A self-sealing rubber hair waving enclosure to receive and hold a curling rod holding a strand of hair and an exothermic hair waving pad and serving to form a tight seal against the escape of steam or moisture from the interior thereof when applied to the head, said enclosure consisting of a box formed of an integral piece of rubber material having a split bottom to receive and clamp a strand of hair adjacent the scalp and serve as a scalp protector having side recesses to receive a curling rod, having a pawl to enable tightening and winding up of said curling rod and to hold said curling rod in position and having a cover flap to enclose the upper end thereof and form a tight seal, the split bottom of said enclosure having a U-shaped member molded therein, the ends of which project to form a latch, the bottom of said box being provided with a plurality of projections serving as feet to support said box.

ARMAND CALDORA. 31
